CRUSHING MACHINERY

Sheldon Stearns, Westfield, N. J.

Application September 9, 1939, Serial No. 294,089

10 Claims. (Cl. 83—10)

My invention relates to improvements in crushing machinery, in particular to the type of crushing machinery known as gyratory crushers in which material is crushed in two or more stages as fully described in my patent, No. 2,147,721, issued February 21, 1939, and the present application contains common subject matter with my abandoned application, Serial Number 108,178, filed October 29, 1936.

In such a multi-stage gyratory crusher there are two or more centrally located conical crushing heads mounted upon a vertical shaft. One end of this vertical shaft is gyrated by means of an eccentric driven directly or indirectly by a motor. The other end of the shaft is centrally and pivotally mounted. Surrounding these conically shaped heads are stationary concaves or crushing surfaces so shaped as to form a large entrance opening between each conical head and its concave at the top, and a continuously narrowing space between each head and its concave towards the lower or discharge end. The shaft with its heads does not revolve, but is so gyrated that the heads move towards and away from their concaves at every point of the circumference, once for every revolution of the eccentric. The minimum clearance between each of the heads and their corresponding concaves for any stage is at their discharge ends. Material to be crushed is introduced at the top or entrance opening between the head and its concave of the first crushing stage, and is gradually crushed to size as it passes through the succeeding crushing stages due to the gyrating motion of the heads, until it is finally discharged from the last stage of the crusher. In other words, the first crushing stage serves to crush the material from its original size to some definite intermediate size, and is discharged from the first crushing stage and allowed to enter the second crushing stage. Two or more stages are used for crushing the material from its original size to the desired final size. The clearance between the concave and the crushing head of the first stage at their discharge ends is so designed and independently adjustable at its discharge point that it does not pass more material at that point than can be accommodated or crushed during an equal interval of time in the second crushing stage. If the crushing of the material is accomplished in more than two stages, the clearance between the concave and the crushing head at their discharge ends of each crushing stage is so proportioned and adjustable that it does not pass more material than can be crushed in an equal interval of time

in the succeeding stage. Material in passing from stage to stage is gradually crushed to a finer size until it reaches the desired degree of fineness when discharged from the last stage. In order to accomplish this the volumetric capacity of the stage and the discharge area must be kept equal. As wear takes place on the crushing surfaces of the heads and concaves the volumetric capacity increases and also the discharge area, which permits a coarser product and larger volume to discharge into the succeeding stage. Therefore it is necessary to keep the volumetric and discharge areas from increasing by adjusting the concave ring upwardly. When it is desired to increase the volumetric capacity and discharge area of any given stage the adjustable concave ring is moved downward. When adjustment in a two-stage crusher is desired in the bottom stage and is accomplished by vertical adjustment of the gyrating shaft, the top stage concave is then adjusted to give it the same capacity as the bottom or second stage. The amount of wear of the crushing surfaces of the heads and concaves in the various stages is not the same over an equal period of time. Therefore it is necessary to adjust each stage individually in order to keep the discharge capacity and volumetric capacity of all stages equal.

The amount of wear of heads and concaves in any given stage depends upon the ratio of reduction and size of the product being crushed. The smaller the product the less will be the percentage of voids or spaces it contains and therefore the wear and friction will be proportionately greater.

In order that a multi-stage crusher may function properly and avoid packing in any stage at any setting all of the stages must have equal volumetric capacity and equal or substantially equal discharge areas with relation to those of the preceding stage. To accomplish this each stage of the multi-stage crusher is constructed so that each individual stage can be adjusted separately to take care of the increase or decrease in volumetric capacity and discharge area.

My invention includes so designing and constructing the concaves of a multi-stage crusher that each of them can be adjusted or moved vertically with respect to the heads entirely independent of one another and without making any vertical adjustment of the heads.

An important advantage in having each concave adjustable independently of any of the others lies in the fact that it may be desirable to change the minimum clearance of any one stage, that is, the discharge opening of any certain stage,

so as to change the amount of material discharged from that stage, when it is found that such a stage discharges more or less material than can be discharged from any of the other stages in equal intervals of time.

This advantage is of especial value in multi-stage crushers since as wear of heads and/or concaves takes place in any stage it is necessary to adjust all stages to have equal capacities or discharge areas as volumetric capacity increases rapidly when the crushing surfaces of the heads and concaves wear to any extent. In a two stage crusher it has been found that the crushing heads and concaves of the second or fine stage will wear approximately twice as fast as those of the first or coarse stage. Therefore, to maintain the crusher at maximum efficiency of operation it is necessary to adjust the concaves of one stage or the other to substantially equalize the discharge areas and volumetric capacities of the stages. Also, the adjustment of the concaves changes the ratio of reduction and permits regulation of the percentages of various sizes of product which may be produced.

The concaves and crushing heads of a stage of a multi-stage crusher may wear sufficiently to increase the volumetric capacity of the stage to such an extent that the succeeding stage of the crusher could not handle the increased capacity, which would result in choking of the crusher with possible breakage of parts. Adjustment of the concaves of the stage having the excessive wear may under the present invention be made to compensate for such wear and reestablish the proper proportions of the various stages.

Another important advantage of having each concave adjustable independently of the position of the other concaves lies in the fact that an operator may wish to re-set the crusher so as to produce a product somewhat finer or coarser than that which the crusher is producing. As an example, let us say that we have a material that is being crushed in a three stage crusher from an initial 4" size to a final $\frac{1}{4}$ " size, and let us say that the minimum discharge clearance between head and concave of the first stage is $2\frac{1}{4}$ ", that of the second stage $\frac{3}{4}$ " and that of the last stage $\frac{1}{4}$ ". Suppose now that it is desired to produce a material, say a finished product of $\frac{1}{8}$ " in size. In order to secure maximum output of the crusher, at the finer setting, it may be advisable to set the minimum discharge clearance between head and concave of the first stage to 2" instead of $2\frac{1}{4}$ ", and that of the second stage to $\frac{5}{8}$ " rather than $\frac{3}{4}$ ", and set the final minimum discharge clearance, that is, the discharge clearance between the head and concave of the third stage, at $\frac{1}{8}$ " instead of $\frac{1}{4}$ ". With independently adjustable concaves in each of the three stages this can be readily accomplished although the necessary amount of vertical adjustment is different for each stage. Changing the ratio of reduction in the stages will change the screen analysis of the finished product, giving a flexibility not found in single stage crushers.

The above data is given only as an illustration. In an actual design of a multi-stage crusher with independently adjustable concaves according to my invention, the designer can determine not only the various diameters necessary for each head and its corresponding concave but also the limits of adjustability of each concave in order to meet the practical requirements of the crusher.

Another advantage of my invention is that

each adjustable concave is supported in a fixed position by a continuous support extending around the entire circumference of the concave and this continuous support is capable of taking either an upward or a downward thrust. Such thrusts may be of considerable magnitude during a crushing operation.

Another advantage of my invention lies in the fact that full adjustment can be made on each concave from the exterior of the machine without having to open the machine in any manner.

Another important advantage of my invention is that each concave can be adjusted by means entirely separate from the means for locking or holding the concave in place after the proper adjustment has been made.

Another important advantage of my invention lies in the fact that by extending the upper part of the concave into a corresponding recess in the frame of the crusher the means for adjusting and locking the concave can be made dust proof and also act as a shield to prevent small crushed material from filling or packing in the clearance space between adjusting means and frame of the crusher.

It should be noted that in a multi-stage gyratory crusher having individually adjustable concaves the usual adjustments that can be secured by the vertical movement of the gyratory shaft and heads are not impaired in the least. Combined adjustments of both the heads and the concaves can be made should it be desired to secure readjustments of the crusher beyond the adjustments that can be secured by moving the concaves alone.

A further object of my invention is to provide a comparatively simple and inexpensive multi-stage gyratory crusher constructed and arranged whereby regulation of the discharge of the second or final crushing stage is provided by adjustment of the gyrating shaft and the crushing heads, while adjustment of the discharge opening of the first stage is provided by adjustable concaves, adjustable independently of the shaft and cones, thereby permitting relative adjustment of the crushing stages for regulating the nature of the product produced by the crusher, and reducing the percentage of fines or small sized particles in the final product, as will be more specifically set out hereinafter.

For a more detailed understanding of my invention reference is to be made to the following description and the accompanying drawings of practical embodiments of the inventive idea, and in which drawings:

Figure 1 is a part sectional view of a three stage gyratory crusher showing particularly the gyrating heads and their corresponding adjustable concaves.

Figure 2 is a half-sectional view of a part of the crusher of Figure 1 showing to an enlarged scale the crushing heads with their corresponding concaves and showing more clearly the method of adjusting the latter.

Figure 3 is a half cross-sectional view of a modified form of Figure 2.

Figure 4 is a cross-sectional view of the crusher along the line 4-4 of Figures 2, 3 and 5.

Figure 5 is a top view of the crusher along the line 5-5 of Figure 2.

Figure 6 is a cross-sectional view of the crusher along the line 6-6 of Figure 1.

Figure 7 is a cross-section through the third stage adjusting wedges showing the bolts used for locking the concave in place.

Figures 8 and 9 show a sectional and end view of the third stage concave showing its adjusting bolts.

Figure 10 is a sectional view of the third stage concave and wedge and also the crusher frame showing the set screws used for limiting the upward movement of the concave.

Figure 11 is a sectional view of the crushing heads of a crusher with their corresponding concaves but showing another method of adjusting the latter.

Figure 12 is a plan view of a shim as used in Figure 11.

Figure 13 is a fragmentary section through the improved crusher illustrating in dotted lines a condition of wear on the concaves and heads.

Figure 13a is a view similar to Figure 13 only showing the concave adjusted to maintain the desired size of the discharge opening of the stage.

Figure 14 is a vertical section through a modified form of the crusher.

Referring to Figure 1, the electric motor for driving the crusher is shown at 1. This motor drives the vertical shaft 2 through the coupling 3. The lower end of the vertical shaft 2 is keyed and fastened to an eccentric bushing 4. The outer surface of the eccentric bushing is journaled in a stationary frame 5, and the inner surface of the eccentric bushing rotates about the hollow gyrating shaft 6. This hollow gyrating shaft permits the driving shaft 2 to pass through it without contact, and carries the crushing heads 7, 8 and 9 on its enlarged tapered portion. The gyrating shaft 6 near its upper end is centered and pivotally mounted in a ball seated bearing 10, and is supported at its threaded upper portion by the nut 11. The motor 1 in turning the shaft 2 rotates the eccentric 4, which in turn oscillates the gyrating shaft 6 about its upper and centrally located pivot 10. The weight of the motor and that of all the rotating and gyrating parts is carried by the spider casting 12 mounted upon the stationary frame or casing 13. Shaft 6 together with the conical heads 7, 8 and 9 can be raised or lowered by means of the adjusting nut 11. Frame 13 is suspended by a number of suspension wire ropes 14 from a fixed support above the crusher and not shown in the figure. Surrounding the crushing heads 7, 8 and 9 are concaves 15, 16 and 17. These concaves are in the form of a continuous ring casting and are separately mounted in the stationary supporting frame 13.

The supporting frame or casing is shown in Figure 1 as made in one piece although the frame can be made in sections bolted together as shown in Figure 11. As the diameters of the head and concave of the first stage are much less than those of the second stage, and the second stage much less than the third stage and so on, the frame of the casing is stepped out in diameter from stage to stage as shown in Figure 1, so as to accommodate the larger heads and concaves of succeeding stages.

As shown in Figure 1, the clearance spaces between the crushing heads and their corresponding concaves of any stage are larger at their top than at their bottom or discharge end. Material is introduced into the space at the top between the crushing head 7 and concave 15 and is crushed to the size of the minimum clearance between this head and its concave at their discharge ends. In multi-stage crushers of my invention the diameter of the discharge of any

stage is considerably smaller than the entrance diameter of the succeeding stage so that material discharged from the first crushing stage cannot drop into the receiving opening of the second crushing stage, but must be conveyed from the discharge of one stage into the receiving opening of the succeeding stage. This can be accomplished by making the upper surface of the succeeding stage with a slight slope and having the surface made of wear resisting material so that material in dropping from the first crushing stage slides along the surface to the outer diameter of the head and into the second stage receiving opening. This conveying or guiding surface need not have much slope because the surface not only gyrates and tilts in all directions but is subject to the usual vibrations accompanying the operation of a gyratory crusher, hence material as it leaves the discharge opening between the crushing head 7 and concave 15 is guided by the sloping surface 18 of the crushing head 8 into the receiving opening of the next crushing stage, that is, into the upper part of the clearance space between the head 8 and the concave 16. In the clearance space between the crushing head 8 and concave 16 the second stage of crushing is performed. The minimum clearance at the bottom of this space is less than the minimum clearance in the first crushing stage. The material after being discharged from the second crushing stage is guided and conveyed by the sloping surface 20 of the gyrating head 9 to the entrance of the third crushing stage, that is, the top clearance space between the crushing head 9 and concave 17. The minimum discharge clearance between the third crushing head 9 and its concave 17 is made so as to deliver the crushed material at the desired size or fineness. The material upon being discharged from the last crushing stage drops upon the inclined surface 22 of the frame and is discharged through a suitable opening 23 of the frame of the crusher.

Figures 2 and 3 show the heads and concaves of Figure 1 to an enlarged scale. Similar numbers in the figures refer to similar parts. Concaves 15, 16 and 17 are vertically adjustable by means of bolts 25, 26 and 27 and set screws 34, 36 and 35 (see Fig. 6), and are held in place by the tapered wedges 31, 32 and 33. These tapered wedges have straight cylindrical surfaces where they are in contact with the straight cylindrical surfaces of the concaves, and they have tapered or conical surfaces on their opposite sides where they fit against conical surfaces on the stationary frame 13 surrounding the concaves. Bolts 28, 29 and 30 serve for raising and lowering these tapered wedges. When the wedge is drawn vertically upward it locks the concave in place and when lowered it loosens the concave. These tapered wedges are arcuate in form extending through almost 90° of arc, so that four of these wedges reach practically around the circumference allowing a small opening or space between each arcuate wedge. The tapered wedges when drawn upward by their bolts support the concaves around their entire circumference and rigidly hold the concaves in a definite fixed position. The minimum clearance between any concave and its corresponding head can be increased by moving the concave vertically upward and the minimum clearance can be decreased by vertically lowering the concave. In adjusting the concave 15 to a new position the nuts on bolts 25 are first slackened and then the nuts on bolts 28 are loosened and by tapping the top of bolts

28 with a hammer the four arcuate wedge pieces are driven downward relieving the locking pressure between the wedges 31 and the ring concave 15. The concave then can be either raised or lowered vertically by means of the nuts on bolts 25 and by adjusting set screws 34 and after the concave 15 is placed in the desired position by proper adjustments of set screws 34 and bolts 25 the arcuate wedges 31 can then be drawn up by means of the nuts on bolts 28 which finally will lock the ring concave 15 in its desired new position.

The re-adjustments of the concave 16 of the second crushing stage and of the concave 17 of the third crushing stage are made in a similar manner as above described for adjusting concave 15 of the first stage. Concave 16 has adjusting bolt 26, set screw 35 and arcuate wedges 32, the latter held in position by bolts 29. Concave 17 has adjusting bolt 27, set screw 36 and arcuate wedges 33, the latter held in position by bolts 30.

In making all these adjustments of the concaves as above described it is not necessary to reach within the crusher but all adjustments can be made externally of the crusher as the means for adjusting and the separate means for locking or fixing each concave all extend through the frame of the crusher and are easily accessible.

It should be noted that the concaves 15, 16 and 17 are shown in Figure 2 as having their upper portions extending into circular recesses 13' of the frame 13. These recesses form overhanging annular lips 13a and are deep enough so that the tops of the concaves are never entirely withdrawn from their recesses when the concaves are adjusted vertically downward. The object of these recesses is to prevent small particles of the crushed material from passing between the top of the concave and the horizontal portions of the frame immediately above the concaves, thereby filling the space between the top of the wedges and the frame. If finely crushed material becomes lodged in the space above the concave and its corresponding wedge it may interfere with a subsequent upward adjustment of the concave. This recess construction need only be used when material is being crushed which pulverizes and cakes easily. Normally this recess construction can be omitted as shown in Figure 3.

The concaves 15', 16' and 17' shown in Figure 3 are similar to concaves 15, 16 and 17 respectively, shown in Figure 2, except that they do not extend into the annular recesses of frame 13 as shown in Figure 2. The annular recesses are omitted in Figure 3.

Figure 4 shows a cross-section through one of the six arms of the second stage crushing head carrying the mantle 8, along the line 4-4 of Figures 2, 3 and 5. These arms extend from the hub of the head to the outer ring of the head upon which is supported the mantle 8. In Figures 2 and 3 the intermediate conical head and the lower conical head are shown with six arms each connecting the hub of the head with its outer rim.

Figure 5 shows a sectional view along the line 5-5 of Figure 2. The arcuate wedges 32 for holding concave 16 in place are shown in Figure 5 in four parts with a slight space between the ends of each part. It also shows three bolts 29 for drawing up each of the arcuate wedge pieces 32 and eight bolts 26 and four set screws 35 for holding the ring concave 16 in place. The arcuate wedge pieces 33 are shown in four parts around the circumference, each part held by three bolts 75 in Figure 11 require the taking apart of the frame

30 and for holding the ring concave 17 eight bolts 27 and four set screws 36 are provided. The conveying surface 18 in Figures 2 and 3 is made of wear resisting material and is built up in three 5 sections for ease of assembly. The same construction is used for the conveying surface 20.

Figure 7 shows a cross-section through the arcuate wedge 33 having a vertical surface against which the ring concave is supported and a sloping surface on the opposite side of the wedge which fits against a corresponding tapered surface on the frame 13 of the crusher. This surface is shown notched so that it can be packed with grease, making the dismantling of this piece easier. The bolt 30 is shown having a head which can receive the blows of a hammer for loosening the wedge should the tapered portion of the wedge have been seized too firmly by the frame of the crusher. The same construction as here shown is used for wedges 31 and 32 and their corresponding bolts 28 and 29.

Figures 8 and 9 show the method of attaching the bolts 27 to the concave 17. The concaves are made of manganese steel castings or other wear resisting material and are difficult to machine. Therefore slots are cast in the concave which can receive the T head of the concave bolts. Concave 17 and T bolt 27 are shown in this 25 figure and the same construction is employed for concaves 15 and 16 and their corresponding T bolts 25 and 26.

Figure 10 is an enlarged cross-section of the concave 17, wedge 33 and set screw 36, of which there are four to each ring concave. These set 35 screws hold the concave from moving vertically upward after it is once set in position and especially during the time when the wedges 33 are drawn into place for locking the concave 17. Set screws 36 also serve in assisting the wedges 40 33 in locking the concave 17 against any vertical movement due to the upward thrust on the concave when it is crushing. Similar set screws 35 are used for holding concave 16 and set screws 34 for holding concave 15 in place.

Figure 11 shows a different method of vertically adjusting the concaves of a multi-stage crusher. In this design the frame 13 of the crusher is made in three sections bolted together as shown in the figure instead of a single piece as shown 50 in Figure 1. The concaves are held in position by shims both above and below the concaves. Concave 15 is held in position by the nest of shims 37 and 38 and concave 16 by the nest of shims 39 and 40, concave 17 by the nest of shims 55 41 and 42. To adjust concave 15 vertically upward some of the shims in the nest of shims 37 are taken out and inserted with the nest of shims 38, thereby raising the concave and for adjusting the concave downward the reverse takes place. That is, some of the shims in the nest of shims 38 60 are taken out and placed with the nest of shims 37. Concaves 16 and 17 are adjusted in a similar manner. The shims in each nest contain some very thin shims, others that are moderate in thickness, and others that are thick, so as to readily make the adjustment to any definite distance desired. These shims, for ease of handling, are not made in a continuous ring but are made in arcuate shape, having three or more shims to the circumference.

Figure 12 shows a plan view of one of these shims of which there are four to the circumference.

Concaves adjusted by means of shims as shown 75 in Figure 11 require the taking apart of the frame

13 before adjustments can be made. However, by the use of means for adjusting the concaves as shown in the previous figures the concaves can be adjusted without disturbing the frame of the machine or any other important part because the adjustable means extend to the exterior of the frame from where the proper adjustments can be made. Some crusher operators may prefer the simplicity of the shim arrangement in spite of the fact that the sections of the frame would have to be unbolted in order to adjust the concaves.

I have found that in definitely locating the concaves of each head by the use of shims it is necessary to have each concave supported or held at both its upper and lower ends by shims. During the crushing operation there is usually a thrust on each concave in an upward direction tending to lift the concave.

Figure 13 illustrates in dotted lines at A and B wear on the adjustable concaves and clearly shows that such wear will cause an increase in the discharge outlet C of the respective stage of the gyratory crusher. The wear in gyratory crushers, particularly on the concaves, is much greater at the lower part of the concave. Such wear on the concaves 15 and the conical crushing heads 7, as indicated by the dotted lines, will increase the capacity of the respective stages as well as increasing the size of the discharge outlet, and since the wear will not be equal in all of the stages of the crusher, will cause an unbalancing of the capacities of the respective stages, resulting in choking of the crusher and also resulting in variation in the size of the product.

In case of such wear, the concave 15 is adjusted by means of its adjusting screw 25, being lowered as shown in Figure 13^a until the discharge outlet C of the stage is of the proper size and cross-sectional area to, first, produce the proper size of the product desired, and, second, to re-establish the balance or proper proportions between the discharging areas of the various stages of the crusher. After the concave has been adjusted to its proper position it is locked therein by means of the adjusting locking screw structure 28.

Figure 14 of the drawings shows a longitudinal section through a modified form of the multi-stage gyratory crusher. This modified form of crusher is a belt or gear driven crusher, the gyrating shaft 100 being driven from the power take-off shaft 101 through the gear mechanism 102, in contradistinction to the direct type of driven crusher shown in Figure 1 of the drawings.

The gyrating shaft 100 has the cone 103 mounted thereon, which has the removable crushing heads 104 and 105 mounted on its outer surface in the usual manner of construction of the crushing heads of gyratory crushers of this type. The heads 104 and 105 are of proper proportionate size to provide a two-stage or multi-stage crusher and a gyrating conveying surface 106 is provided for conveying and distributing the crushed material from the first stage of the crusher to the inlet of the second stage of the crusher. The concave 107 of the second stage of the crusher is not shown as adjustable, but the concave 108 of the first stage of the crusher is adjustable.

The adjustment of the size of the final discharge 110 of the crusher and consequently the size of the final product is regulated by adjustment of the crushing head assembly, comprising the gyrating shaft 100, cone 103 and the crushing

cones 104 and 105, through the medium of the adjustment providing structure shown at 111. This adjustment providing structure 111 comprises the threaded end 111' of the shaft 100 and the nut 111", which cooperates with the bearing structure 111b.

The adjustment of the concave 108 of the first stage of the multi-stage gyratory crusher permits relative adjustment of the crushing stages of the crusher for varying the ratio of one stage to the other for regulating the nature of the product produced by the crusher. By variation of the ratios of the discharge of the first stage and the discharge opening of the second or final stage, different types of product may be obtained.

For example, when crushing a hard rock, operating with the concaves set so that the first stage receives a feed of plus 1 1/4" minus 2 1/2" and discharge opening on closed side set at 1 5/8" and with the final discharge of the second stage set at 7/8", the crusher produced a final product of which 34 per cent was fines. That is, 34 per cent of the final product was minus 1/4" in size. By adjusting the concave to reduce the discharge opening of the first stage to 1 1/8" closed side, without any variation of the final discharge of the second stage from its 7/8" setting, the percentage of fines was very materially reduced and under such operating conditions only 19 per cent of the final product was minus 1/4" in size.

The conditions just set out vary with different types of material and size of feed to the crusher and by providing comparatively easy and inexpensive adjustment of the first stage, the crusher may be adjusted to produce a fine or coarse product without changing the discharge opening of the second stage.

Also the adjustability of the concave 108 permits it to be adjusted as wear occurs on it and the crushing head 104 for maintaining the proper proportion between the discharge outlet 109 of the first stage and the discharge outlet 110 of the second stage.

The concave 108 has an annular flange 112 formed thereon near its outer end. This flange projects outwardly and abuts the lower ends of the arcuate locking wedges 113. The concave is adjusted by means of the bolts 114 and the nuts 115 thereon into the desired position and is locked therein by means of the locking wedges 113 and the locking screws 116.

The shell 117 of the modified form of belt driven multi-stage gyratory crusher has a plurality of ports or openings 118 therein opening into the non-crushing zone 118' between the first and second crushing stages of the crusher. In the drawings only one of the openings 118 is shown, but it is to be understood that any number of them may be provided, depending upon the requirements of each individual machine.

The openings or hand holes 118 serve a number of functions or purposes. That is, they permit the obtaining of a sample of the material being crushed as it is discharged from the first stage so as to enable the operator to determine the various sizes of product being produced by the first stage or by the stage of the crusher at the discharge of which the openings enter the non-crushing zone, 118'. Then also, these hand holes or ports permit removal, manually, of all loose material or product being crushed which has failed to enter the succeed-

ing stage in instances where the crusher has stopped due to sudden power cut-off or other causes, and they permit removal of any foreign material which has passed the preceding stage and is of such shape or size that it cannot enter and pass through the succeeding stage.

These hand holes or openings also serve the function of permitting an operator to determine whether the volume of material discharged from the preceding stage is too great to be accommodated by the succeeding stage, in that in instances where an excess amount of material is being delivered by the preceding stage some of this material, which can not be taken by the succeeding stage, will flow out of the openings 118, which clearly indicates to the operator that there is an excess volume of material passing through the preceding stage and that this preceding stage requires adjustment of its discharge opening so as to regulate the volume of discharge in accordance with the capacity of the succeeding stage without accumulating in the non-crushing space or zone 118'.

The openings 118 are inspection openings which permit equalizing capacities by independent adjustment of the stages so that material will flow through all discharge openings in an equal interval of time, thereby preventing accumulation of the product being crushed between stages.

In Figure 14 the opening 118 is shown as closed by a pivoted closure flap 119. However, if it is desired this closure flap may be eliminated and the openings left open to the exterior of the casing at all times.

In accordance with the provisions of the patent statutes, I have described the principle of operation of my invention, together with the apparatus which I now consider to represent the best embodiments thereof; but I desire to have it understood that the apparatus shown is only illustrative, and that the invention can be carried out by other means.

What I claim as new and desire to secure by Letters Patent of the United States is:

1. In a gyratory crusher, a stationary frame, a plurality of crushing heads of progressively larger diameters mounted on a gyrating shaft, each crushing head surrounded by a suitable stationary concave cooperating therewith to form a tapering crushing zone and so as to form definite crushing stages so designed and constructed that the material to be crushed passes through the crushing stages in sequence and having the active discharge areas of all stages proportioned to pass an equal quantity of material in an equal interval of time, said crusher having a non-crushing area between the adjacent crushing stages and each crushing stage discharging through its corresponding non-crushing area into the succeeding crushing stage, and means adjustably connecting the concave of the initial crushing stage of the crusher to said frame for vertical adjustment of the concave relative to the crushing head whereby the quantity of material crushed by the crusher in a given period of time and the size of the material may be varied, said means comprising a wedge-shaped member engaging the non-crushing back of the concave and said stationary frame for moving the concave upon movement of the wedge, and adjustable means connecting the wedge and stationary frame.

2. In a multi-stage gyratory crusher, a gyrating shaft, a number of crushing heads mounted on said shaft, said heads being of increasing diameter from stage to stage from the top down-

ward, a stationary frame surrounding the gyrating shaft and comprising an annular portion of substantially constant diameter for each stage, said annular portions being of increased diameter in succeeding stages from top to bottom and joined with each other by outwardly extending ledges, annular grooves provided in the inner sides of said ledges, a ring shaped concave surrounding each crushing head and being spaced from its corresponding annular frame portion, said concaves being adjustably suspended from the ledges of the frame and having their tops extending into and cooperating with the grooves to prevent ingress of dust and crushed particles into the space between each concave and its corresponding annular frame portion, and means for holding each concave in adjusted position located in the space between each concave and its annular frame portion, said holding means closing the bottom of the spaces whereby dust and crushed particles are excluded.

3. In a gyratory crusher, a gyrating shaft, a substantially conical crushing head on said shaft, a stationary frame comprising an annular portion of substantially constant diameter surrounding said crushing head, said frame provided with a ledge extending inwardly from said constant diameter portion and having an annular groove in its inner side, a ring shaped concave surrounding said crushing head and being spaced from said annular frame portion, said concave adjustably suspended from said ledge and having its top extending into and cooperating with said groove to prevent ingress of dust and crushed particles into the space between the concave and annular frame portion, and means for holding said concave in adjusted positions located in the space between the concave and the annular frame portion, said holding means closing the bottom of the space whereby dust and crushed particles are excluded.

4. In a multi-stage gyratory crusher, a gyrating shaft, a plurality of crushing heads mounted on said shaft, said heads being of increasing diameter from the top downward, a ring shaped concave surrounding each crushing head, means for vertically and independently adjusting each concave, and means movable independently of the concaves for circumferentially supporting and locking each concave in adjusted position.

5. In a multi-stage gyratory crusher, a gyrating shaft, a plurality of crushing heads mounted on said shaft, said heads being of increasing diameter from the top downward, a ring shaped concave surrounding each crushing head, means for vertically and independently adjusting each concave, and means movable independently of the concaves for circumferentially supporting and locking each concave in an adjusted position, a frame surrounding said gyrating shaft, crushing heads and concaves, said frame provided with means for preventing crushed particles from getting behind the concaves and the independently movable concave supporting and locking means.

6. A gyratory crusher having two or more crushing heads of progressively substantially larger diameters mounted on a gyrating shaft, each crushing head surrounded by a suitable stationary concave so as to form definite crushing stages and having every part of the crushing surfaces of each crushing stage of a larger diameter than any part of the crushing surfaces of the preceding stage, and so designed and constructed that the material to be crushed passes through the crushing stages in sequence from the smallest

diameter stage to the next larger one, and having the active discharge areas of all stages proportioned to pass an equal quantity of material in an equal interval of time, a stationary frame surrounding said concaves, means for vertically and independently adjusting each concave relative to the frame, and separate means movable independently of the concaves for continuously and circumferentially supporting each concave.

7. A gyratory crusher having two or more crushing heads of progressively substantially larger diameters mounted on a gyrating shaft, each crushing head surrounded by a suitable stationary concave so as to form definite crushing stages and having every part of the crushing surfaces of each crushing stage of a larger diameter than any part of the crushing surfaces of the preceding stage, and so designed and constructed that the material to be crushed passes through the crushing stages in sequence from the smallest diameter stage to the next larger one, and having the active discharge areas of all stages proportioned to pass an equal quantity of material in an equal interval of time, a stationary frame surrounding said concaves, means for vertically and independently adjusting each concave relative to the frame, and separate means movable independently of the concaves for continuously and circumferentially supporting each concave, said stationary frame comprising outwardly extending ledges provided with recesses in their inner surfaces receiving the upper ends of said concaves, said recesses being of such depth that in no adjusted position will the upper edges of the concaves be out of the respective recesses.

8. In a multi-stage gyratory crusher, a plurality of concaves, a stationary frame surrounding said concaves and provided with outwardly extending ledges, means for vertically and independently adjusting each concave, and wedge means engaging the stationary frame and concaves and movable independently of the concaves for continuously and circumferentially supporting each concave, said outwardly extending ledges being provided with recesses receiving the upper ends of the concaves and said wedges fitting snugly between the concaves and the frame at the bottom of the concaves whereby dust and

crushed particles will be excluded from between the concaves and the wedges and the frame.

9. In a gyratory crusher, a stationary frame, a plurality of crushing heads of progressively larger diameters mounted on a gyrating shaft, each crushing head surrounded by a suitable stationary concave so as to form definite crushing stages so designed and constructed that the material to be crushed passes through the crushing stages in sequence and having the active discharge areas of all stages proportioned to pass an equal quantity of material in an equal interval of time, said crusher having a non-crushing area between the adjacent crushing stages and each crushing stage discharging through its corresponding non-crushing area into the succeeding stage, and concave adjusting means connecting the concave of the initial crushing stage to said frame whereby the concave may be adjusted to vary the quantity of material crushed in said stage in any given time and the size of the material crushed may be varied, said adjusting means including wedge-shaped members between the concave and stationary frame and constructed and arranged whereby the pressure exerted against the concave by the material being crushed will cause a wedging action of the adjusting means on the concave to bind it in its adjusted position against accidental movement relative to the frame.
10. In a gyrating crusher having a plurality of crushing stages formed by crushing heads mounted on a common gyrating shaft and co-operating with stationary concaves to form definite crushing stages, a supporting frame, means connecting said gyrating shaft to said frame for supporting the shaft and to provide adjustment thereof to regulate the size of the discharge area of the final stage of the crusher, means adjustably supporting the concave of the first of said stages to permit adjustment of the size of its discharge opening independent of adjustment of the size of the discharge of the final stage, said means comprising a wedge-shaped member engaging the non-crushing back of the concave and said stationary frame for moving the concave upon movement of the wedge, and adjusting means connecting the wedge and stationary frame.

SHELDON STEARNS.
